United States Patent Office.

JOHN C. JOHNSON, OF PHILADELPHIA, PENNSYLVANIA.

Letters Patent No. 73,726, dated January 28, 1868.

IMPROVEMENT IN SODA-FOUNTAINS.

The Schedule referred to in these Letters Patent and making part of the same.

TO ALL WHOM IT MAY CONCERN:

Be it known that I, JOHN C. JOHNSON, of the city of Philadelphia, in the county of Philadelphia, and State of Pennsylvania, have invented a new and useful Improvement in Soda-Fountains; and I do hereby declare that the following is a full, clear, and exact description thereof, reference being had to the accompanying drawings, making part of this specification, in which—

Figure 1 is a diametrical section through the fountain, adapted for receiving the movable bottom.

Figure 2 is a similar view, showing the bottom applied to the fountain.

Figure 3 is a section through fig. 1, in the horizontal plane indicated by red line, x, showing the internal elliptical plate for sealing the bottom of the fountain.

Figure 4 is a bottom view of the fountain.

Figure 5 is a perspective view of the bottom portion of the fountain, showing the insertion of the elliptical sealing-plate.

Similar letters of reference indicate corresponding parts in the several figures.

This invention relates to an improvement on the construction of portable vessels which are designed for containing soda-water and other aerated mineral-waters under considerable pressure, by which improvement such vessels can be conveniently constructed in a more durable and substantial manner than hitherto, and after being lined on their interior surfaces, to prevent corrosion, the openings through them, which admit of the application of such lining, can be hermetically sealed, and made perfectly secure against leakage.

The nature of my invention consists in constructing a fountain of one piece of metal, with an opening through one end, of such size as to admit of access to its interior surface, for lining it with some non-corrodible enamel, which opening is of such form as to admit of the insertion through it of an oblong plate, which, when properly adjusted, and fitted upon an internal shoulder surrounding the opening, and firmly clamped in place, will effectually seal said opening against the escape of the contents of the fountain, as will be hereinafter described.

To enable others skilled in the art to understand my invention, I will describe its construction and operation.

The fountain A B, shown in figs. 1 and 2, is cast, or otherwise constructed, of one piece of metal, with a dome-shaped top and a contracted bottom, terminating in a flaring stand or foot-piece, B, surrounding an elliptical opening, c. This opening through the bottom of the fountain should be made of such size as to allow access to the interior of the fountain, for lining its surface with any suitable enamel, or other substance which will prevent corrosion. Surrounding the elliptical opening c is a shoulder or offset, g, which is adapted for receiving upon it and forming a seat for a plate, C, which corresponds in shape to the hole c, but which is slightly larger than this hole, as shown in figs. 2 and 3. This plate C being made larger in area than the hole c, which it is designed to cover, it is necessary to make this hole and its sealing-plate of an oblong shape, so that the latter can be inserted through the hole edgewise, as shown in fig. 5, and then adjusted and fitted into its seat. In the centre of the bottom side of the elliptical plate C is an elevation, e, which is drilled out and screw-tapped, for receiving a short square-headed screw, b. This screw is designed for drawing the plate C down firmly upon its seat, and holding it there, for which purpose a circular external plate, D, (or a transverse bar) is applied to the bottom of the fountain, through which plate screw b is passed, and the two plates C D clamped firmly in their places, as shown in fig. 2. To make this joint perfectly tight, without the necessity of grinding the impinging surfaces, a packing of rubber, or other suitable substance, is introduced between the plate C and its seat, as shown in fig. 2. This packing will be compressed when the screw b is set up tight, and a perfectly tight joint will be made, which will prevent the escape of gas or liquid from the bottom of the fountain.

It will be seen from the above description that the greater the pressure within the fountain, the firmer will the cover C be held upon its seat. This arrangement of the plate C upon the inside of the fountain, requires but a single screw, b, applied as described, for holding it in place, by removing which screw access can be had to the interior of the fountain whenever it is not charged. The lower end of the draw-off pipe, shown in red lines, fig. 2, is depressed below or on a level with the upper surface of plate C, just over a recess made in this plate, so that the fountain can be completely exhausted of its liquid contents.

Having described my invention, what I cla. : as new, and desire to secure by Letters Patent, is—

A soda-water fountain, which is constructed with a contracted perforated bottom, and a flanged foot-piece, B, and provided with a removable bottom, C, fitted within said fountain, upon a seat which surrounds an oblong opening, c, and held in place by means of a screw, b, and external cap or bar, D, substantially as described.
